UNITED STATES PATENT OFFICE.

EDWIN J. GRENDING, OF COLFAX, ILLINOIS.

GATE-LATCH.

1,348,715.

Specification of Letters Patent.

Patented Aug. 3, 1920.

Application filed January 31, 1916. Serial No. 75,371.

To all whom it may concern:

Be it known that I, EDWIN J. GRENDING, a citizen of the United States, residing at Colfax, in the county of McLean and State 5 of Illinois, have invented certain new and useful Improvements in Gate-Latches, of which the following is a specification.

The present invention relates to locks and latches, and more particularly to gate 10 latches.

An object of this invention is to provide a new and improved gate latch constructed in such a manner as to permit opening of the gate from either side without the provision of extra knobs, levers or the like.

Another object of this invention is to provide a device of the class above described which is simple in construction, effective in operation, and cheap to manufacture and in 20 stall.

Other objects and advantages of this invention will appear from the following detail description and claim, taken with an inspection of the accompanying drawing, in 25 which—

Figure 1 is a perspective view of my improved gate latch, and

Fig. 2 is a transverse sectional view of a gate showing my improved latch association 30 therewith.

Referring more particularly to the drawing, wherein similar characters of reference designate like and corresponding parts throughout the various views, 1 designates 35 the jamb or frame of a door or gate and 2 the gate. The device of my invention, of course, may be applied to any gates or doors of the hinged type.

My latch includes a latch member, design- 40 nated 3 in its entirety, of bell crank shape having a latch arm 4 and an operating arm 5. The latch member 3 is pivoted between brackets 6 on a screw 7, said brackets being secured on the gate 2 by means of 45 screws 8 or the like. The latch arm 4 is provided on its free end with a tapered enlargement 9 forming a shoulder 10 for engagement with a staple 11 or similar projection carried by the frame 1, the inner edge 50 of the enlargement adjacent the shoulder being curved toward the outer end to facilitate engagement of the enlargement with the staple when the door is being closed.

From an inspection of the operating arm 55 5 it will be noted that the same is slightly

arcuate throughout its length, which serves to position the free end of said arm away from the surface of the gate 1 to permit free movement of the arm 5 at times. The arm 5 is provided preferably midway its length 60 with a knurled enlargement 12 forming a finger engaging portion for unlatching the gate and forcing the latter open.

In order to unlatch and open the gate from the side opposite the latch member, I 65 provide a rod 13 operating in an opening transversely of the gate, said rod having one end bifurcated as at 14 for engagement with the free end of the arm 5, a screw 15 or the like pivotally connecting said arm and said 70 rod. Washers 16 and 17 are placed on the opposite faces of the gate and said rod 13 operates through said washers, the latter serving as bearings. A coiled spring 18 is wound about the rod 13 between the bifur- 75 cated end 14 and the washer 16 to maintain the latch arm normally in engaging position. The washer 17 is prevented from dislodgment by means of nails or the like 19. In order to pull the rod 13 to unfasten the 80 latch, I provide a finger engaging ring 20 carried on the free end of said rod.

In order to unlatch the gate from the side on which the latch member is mounted pressure is applied to the arm 5 by placing a 85 finger or the thumb against the knurled enlargement 12. This will move the shoulder 10 out of engagement with the staple 11 thereby both unlatching and opening the gate. To open the gate from the opposite 90 side the ring 20 is grasped and pulled which will automatically unlatch and open the gate. I desire to call particular attention to the peculiar formation of the latch member wherein the arm 5 is curved, which allows 95 the pivot 7 to be placed close to the door or gate. Of course, when the gate is pushed into closed position it is automatically latched.

From the above description taken in connection with the accompanying drawings, it is thought that a clear and comprehensive understanding of the construction, operation and advantages of my invention may be had, and while I have shown and described my 100 invention as embodying a specific structure, I desire that it be understood that I may make such changes on said structure as do not depart from the spirit and scope of the invention as described.

What I claim as my invention and desire to secure by Letters Patent is:

A latch of the character described, comprising a latch member of substantially bell crank shape having one arm of hook form to provide a latch portion and the other arm constituting an operating portion, a bracket pivotally supporting the latch member adjacent to the point of juncture of the latching and operating portions thereof and adapted to be secured to a movable part, a staple adapted to be secured in a fixed part and engageable by the latch portion of said latch member, an actuating rod adapted to be slidably fitted through the movable part and

having a forked extremity straddling the operating portion of said latch member, a pivot connecting the forked extremity of the rod to the free extremity of the latch portion, a spring active upon the rod and the movable part for normally sustaining the latching portion of the latch member in position for positive engagement with the staple, a knurled enlargement formed on the operating portion of the latch member spaced from the end pivotally connected with the rod and on the outermost edge thereof. 20 25

In testimony whereof I affix my signature hereto.

EDWIN J. GRENDING.
